UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

1,405,518.

Specification of Letters Patent. Patented Feb. 7, 1922.

Application filed September 28, 1920. Serial No. 413,378.

To all whom it may concern:

Be it known that I, DAVID S. KENNEDY, a citizen of the United States, residing at Brooklyn, in the county of Kings and State 5 of New York, have invented certain new and useful Improvements in Typographical Distributing Machines, of which the following is a specification, reference being had therein to the accompanying drawing.

10 My invention relates to typographical machines, such as linotype machines of the general organization represented in U. S. Letters Patent to O. Mergenthaler No. 436,532, wherein circulating matrices are released 15 from a magazine in the order in which their characters are to appear in print and then assembled in line, the composed line transferred to the face of a slotted mold, the mold filled with molten metal to form a slug 20 or linotype against the matrices which produce the type characters thereon, and the matrices thereafter returned through a distributing mechanism to the magazine from which they started.

25 The present improvements are directed more particularly to the distributing mechanism of such machines, and involves a new arrangement for sorting or separating matrices of two different sets, whether said 30 sets constitute entirely distinct fonts or different portions of the same font. According to the scheme contemplated, the matrices of one set are formed with projecting ears located at the right side of the matrix bodies, 35 while those of the other set are formed with projecting ears located at the left side of the matrix bodies, and means are provided to cooperate with the matrices while in course of distribution and deliver them at 40 different points according to the location of their projecting ears. The exact construction and arrangement of the parts will be best understood from the detailed description to follow.

45 Referring to the drawings:

Fig. 1 is a side elevation of the upper portion of a linotype machine presenting one embodiment of my invention;

50 Fig. 2 is an enlarged longitudinal section taken through a portion of the magazine, magazine entrance and distributor bar, and showing in detail the manner in which the matrices are distributed into the magazine;

Fig. 3 is a view similar to Fig. 2, showing

the use of matrices of different sizes or thicknesses; 55

Fig. 4 is a perspective view of two matrices taken from the different matrix sets and formed with the same tooth-combination; 60

Fig. 5 is a side elevation of the upper portion of a linotype machine presenting another embodiment of my invention;

Fig. 6 is a front view of certain portions of the primary distributor therein employed; 65

Figs. 7 and 8 are sections taken on the line x—x of Fig. 5, and showing matrices in course of distribution; and

Fig. 9 is a view similar to Fig. 4, but 70 illustrating matrices formed with different or unlike tooth-combinations.

The matrices X and Z illustrated in Fig. 4 are representative of the two different matrix sets herein employed. As will be observed, the matrix X is of the same form as heretofore, being formed at its upper end with the customary tooth combination X¹ and on its opposite edges with the usual projecting ears X², which latter as before 80 are located at the right side of the matrix body (the following side during composition and the leading side during distribution). The matrix Z is likewise formed at its upper end with a tooth combination Z¹ and on its 85 opposite edges with projecting ears Z², and differs from the matrix X only in respect to the location of its projecting ears Z², which in this instance are located at the left side of the matrix body, the tooth combination Z¹ being identical with the tooth-combination X¹. The remaining matrices of the two groups are constructed in precisely the same way,—that is to say, the tooth combinations of the matrices of one set (although of course differing from each other as between the respective matrices of such set) are identical with those of the matrices of the other set, while the projecting ears of the corresponding matrices of the two 90 sets (i. e. those having the same tooth-combination) are disposed at opposite sides of the matrix bodies to distinguish them as to form. It is this difference in form which is relied upon in sorting or separating the matrices according to set, as will subsequently 95 appear.

In the embodiment illustrated in Figs. 1

to 4, the matrices of both sets are stored in the magazine A and are returned thereto from the distributor bar B through the intermediate magazine entrance D. The bar 5 B is of ordinary construction, being of V-shape in cross-section and formed with successive tooth or distributing combinations B¹ designed to cooperate with the tooth combinations X¹ and Z¹ of the matrices X 10 and Z in effecting their release at different points in the length of the bar. The magazine A, like the ordinary magazine, comprises two parallel side plates A¹ formed on their inner faces with opposing grooves A² 15 providing a series of channels wherein the matrices are stored and which are arranged in different vertical planes throughout the width of the magazine; but unlike the ordinary magazine, these grooves A² are separated by two different kinds of ribs A³, and A⁴, the latter serving to divide the grooved magazine channels into pairs, and the former to separate the adjoining channels of each pair from each other. The 20 magazine entrance D, as usual, comprises two parallel side plates D¹ and a series of intermediate parallel partitions D², but unlike the ordinary entrance, the partitions D² are arranged in distinct pair as shown, so 25 as to provide a series of straight or unrifled channels or conductors leading from the respective bar combinations B¹ and each communicating with a pair of adjoining magazine channels. In providing for their 30 proper distribution, the matrices X are stored in every other channel of the magazine, and the matrices Z in the intermediate channels; or stated differently, each pair of adjoining magazine channels is 35 devoted to the corresponding matrices of the two sets. According to this construction and arrangement of the parts, the matrices of both sets are distributed into the same channels of the magazine entrance and then 40 directed by their differently located projecting ears into the appropriate channels of the magazine. For example, taking the first entrance channel in Fig. 2, a matrix from each set is shown passing through such 45 channel, both of said matrices having been released at a common point from the distributor bar B, due to the fact that their tooth combinations X¹ and Z¹ are identical. (See Fig. 4.) However, by reason of the 50 different location of their projecting ears X² and Z², the two matrices are caused to enter different ones of the two cooperating magazine channels, the leading matrix Z (which has its projecting ears located at the 55 left side) being guided into the left magazine channel, and the following matrix X (which has its projecting ears located at the right side) being guided into the right magazine channel. This same action takes 60 place throughout the machine, matrices of 65

both sets being dropped by the remaining bar combinations into the corresponding entrance channels and then directed into the appropriate magazine channels. In this way, it is possible to employ a distributor 70 bar having any given number of combinations in connection with a magazine having twice the number of matrix channels,— a feature of great advantage. For example, by constructing the parts in the foregoing 75 manner, the ordinary distributor bar which is formed with at least ninety different tooth combinations would be enabled to distribute matrices into a magazine formed with one hundred eighty matrix channels; or in the case of a distributor bar formed with one hundred twenty six tooth-combinations (which is the maximum number according to the seven-rib system), the magazine could be provided with two hundred fifty two 80 matrix channels. In this connection, it may be remarked that in machines as heretofore constructed, the number of matrix channels in the magazine has always been equal to the number of tooth combinations on the distributor bar, so that the capacity of such machines is necessarily limited to that extent.

While, as just pointed out, the present arrangement permits the employment of 95 twice as many magazine channels as there are distributing combinations, my invention of course does not require that the full capacity of the machine be thus availed of. That is to say, it is not necessary to provide 100 the magazine with two channels for each combination of the distributor bar, but such arrangement may be restricted to any selected number of bar combinations and in fact to one only if desired. For instance, 105 it is very common to store matrices bearing the same character in two adjoining magazine channels and to draw the matrices from the two channels alternately during composition. It can be seen that the present 110 arrangement is well adapted to carry out the distribution of such matrices into their different magazine channels, and this without requiring the addition of any further bar combinations or any differentiation between 115 the tooth-combinations of the matrices, as heretofore necessary. It is apparent, therefore, that the extent of use of my improvements will depend essentially upon the particular purpose they are intended to subserve. In other words, if it is a case of employing as many magazine channels as possible for any given number of distributing combinations, then the magazine will be provided with two channels for each combination of the distributor bar; but if it is a case merely of adding a limited number of magazine channels without having to add any further distributing combinations, then 120 the magazine will be provided with fewer 125 channels. In the latter case, the number of channels will depend upon the number of distributing combinations employed, and the number of 130

pairs of channels to cooperate with the selected combinations of the distributor bar. I may mention that it is my present intention to make use of the full number of 5 magazine channels so as to store in one magazine as many different matrices as possible. It hardly needs to be stated that the two matrix sets may constitute distinct fonts or different portions of the same font; in 10 fact they may carry characters of any desired description.

In Fig. 2, the matrices are shown as being of uniform thickness, but as clearly indicated in Fig. 3, they may vary widely in thickness 15 and still be distributed in the same way. Indeed, those matrices designed to pass through the same entrance channel may be of different thicknesses if desired,—see for example the matrices X and Z shown as passing 20 through the third entrance channel in Fig. 3. The handling of the matrices in such case is made possible by the tapering of the magazine ribs A³, which as shown are brought to a point and located centrally of 25 the entrance channel so as to cooperate with the projecting ears of the matrices and deflect them into one or the other of the magazine channels according to the location of their projecting ears.

30 In the embodiment illustrated in Figs. 5 to 9, the matrices X are stored in the lower magazine E, and the matrices Z in the upper magazine F, which magazines are connected by means of the magazine entrances G and H 35 to the separate secondary distributors J and K, respectively. These parts may be of any desired construction, such for example as embodied in the commercial machines of this class, in which each magazine is formed with 40 ninety different matrix channels and the cooperating distributor with as many different tooth combinations, and in which the matrices stored in the magazines are ordinarily of different fonts. My present improvements 45 contemplate an improved form of mechanism by which matrices from the two magazines are first separated according to form or font and then delivered to their appropriate secondary distributors. In the 50 present instance, I employ a primary distributor which simply comprises a short bar or rail L of customary V-shape in cross-section and a set of conveying screws M for propelling the matrices therealong. This 55 bar L is provided as usual with the full complement of ribs or teeth L¹ to cooperate with the tooth combinations of the matrices, but these teeth L¹ (unlike those of the ordinary primary distributor bar) are continuous 60 throughout so as to release the matrices of both sets at a common point. Thus, taking the two matrices shown in Fig. 9 by way of example, although their respective tooth combinations X¹ and Z¹ differ, both will be 65 released from the bar L at the same point,

due to the continuous character of the ribs L¹ which maintain their engagement with the tooth combinations of the matrices until the latter have completely traversed the bar. Accordingly, each matrix of each set, irrespective of its particular tooth combination, is released from the bar L at the same point. As the matrices are released from the bar L, they drop directly into two underlying tubes or conductors N and O which are constructed 70 to guide the matrices by their projecting ears, each tube having its edges bent over to provide grooves wherein the matrix ears engage and being open at one side to allow the matrix body portions to project outwardly 75 therefrom. As shown in the several figures, these two tubes are arranged with their open sides facing each other, being straight and disposed in immediate contact at their upper ends for a distance equal at least to the 80 length of a matrix, and then curved forwardly and backwardly to make connection with the respective secondary distributors. It may also be noted that the tube N is offset laterally from the tube O at or near the point 90 where the two diverge so as to allow the matrices to pass therealong without interference.

According to the above construction and arrangement of the parts, the matrices of 95 both sets are all released from the bar L at a common point, and then dropped directly into the two tubes as permitted by the open character of their opposing sides, becoming 100 engaged with one or the other of the two tubes according to the location of their projecting ears. That is to say, a matrix Z (which has its ears Z² located at the left side) will be carried along the tube O to the distributor K; while a matrix X (which has its 105 ears X² located at the right side) will be carried along the tube N to the distributor J. In this way, the matrices of the respective sets are separated from each other and then restored to their corresponding distributor 110 for return to the appropriate magazine.

I have thus shown two quite different embodiments of my invention, although both embody the same underlying principle. However, these embodiments have been illustrated merely by way of example and as applied to different classes of machines, and it will be obvious that the invention is susceptible of many other modifications and alterations which will still be comprised within its 115 spirit. For instance, an arrangement similar to that last described might be employed in distributing sorts matrices into different receptacles, which result could be accomplished by modifying the sorts matrices in the above 120 manner and arranging the two tubes so as to receive them from any selected point of the distributor, say the extreme end of the bar B in the first embodiment, or that end of either 125 of the two secondary distributor bars J and 130

K in the second embodiment. Again, by employing a series of tubes N and O, the matrices of the two sets might be distributed into a pair of superposed magazines directly from a single distributor bar, which arrangement would involve merely the use of a pair of such tubes in connection with each tooth combination of the ordinary distributor bar. Many such variations and adaptations of my invention will readily suggest themselves to those skilled in the art without departure from its scope. I therefore desire it to be understood that I do not limit myself to any specific form or arrangement except in so far as such limitations are specified in the claims.

Having thus described my invention, its construction and mode of operation, what I claim is as follows:

20. 1. In a typographical distributing machine equipped with matrices formed with projecting ears on their opposite edges, the combination of a magazine comprising two parallel side plates formed on their inner faces with opposing grooves providing a series of matrix channels arranged in different vertical planes throughout the width of the magazine, a cooperating magazine entrance comprising two parallel side plates 30 and intermediate partitions providing a series of straight or unrifled channels through which the matrices pass to the magazine, and means for distributing the matrices into the respective entrance channels, at least one 35 of said entrance channels communicating with two adjoining magazine channels, and the projecting ears of the matrices distributed into said channel being located at the left side of some and at the right side of others so as to enable the matrices to enter one or the other 40 of the two magazine channels according to form.
2. In a typographical distributing machine equipped with two sets of matrices, each formed with projecting ears on its opposite edges, the combination of a magazine comprising two parallel side plates formed on their inner faces with opposing grooves 50 providing a series of matrix channels arranged in different vertical planes throughout the width of the magazine, the matrices of one set occupying every other channel, and those of the other set the intermediate channels; a cooperating magazine entrance 55 comprising two parallel side plates and intermediate partitions providing a series of straight or unrifled channels through which the matrices pass to the magazine, there being one such entrance channel for each pair 60 of adjoining magazine channels, and means for distributing the matrices of the two sets into the respective entrance channels, the said matrices having their projecting ears located at opposite sides thereof in the respective sets so as to enter the appropriate

channels of magazine as they pass from the magazine entrance.

3. In a typographical distributing machine equipped with matrices, each formed at its upper end with a tooth-combination 70 and on its opposite edges with projecting ears, the combination of a magazine comprising two parallel side plates formed on their inner faces with opposing grooves providing a series of matrix channels arranged 75 in different vertical planes throughout the width of the magazine, a cooperative magazine entrance comprising two parallel side plates and intermediate partitions providing a series of straight or unrifled channels 80 through which the matrices pass to the magazine, and an overlying distributor bar formed with a series of tooth-combinations 85 to cooperate with those of the matrices in distributing said matrices into the respective channels of the magazine entrance, at least one of said entrance channels communicating with two adjoining magazine channels, and certain of the matrices being provided with the same tooth-combination 90 so as to be distributed into said entrance channel, and the projecting ears of said matrices being located at the left side of some and at the right side of others so as to enable the matrices to enter one or the other 95 of the two magazine channels according to form.

4. In a typographical distributing machine equipped with two sets of matrices, each formed at its upper end with a tooth combination and on its opposite edges with projecting ears, the combination of a magazine comprising two parallel side plates formed on their inner faces with opposing grooves providing a series of channels arranged in different vertical planes throughout the width of the magazine, the matrices of one set occupying every other channel, and those of the other set the intermediate channels, a cooperating magazine entrance 100 comprising two parallel side plates and intermediate partitions providing a series of straight or unrifled channels through which the matrices pass to the magazine, there being one such entrance channel for each pair 105 of adjoining magazine channels, and an overlying distributor bar formed with a series of tooth combinations to cooperate with those of the matrices in distributing said matrices into the various channels of 110 the magazine entrance, the respective matrices of the two sets being provided with the same tooth combinations so as to be distributed into the same entrance channels and having their projecting ears located at opposite sides thereof in the respective sets so as to enter the appropriate channels of the magazine as they pass from the magazine entrance.

5. In a typographical distributing ma- 130

chine equipped with matrices each formed with projecting ears, the said ears being located at the left side of some and at the right side of other of said matrices, the combination of a channel along which the matrices travel endwise, and means to cooperate with the matrices in their endwise travel and deliver them at one point or another according to the location of their projecting ears.

6. In a typographical distributing machine equipped with matrices each formed with projecting ears on its opposite edges, the said ears being located at the left side of some and at the right side of other of said matrices, the combination of means for transporting the matrices through the machine, and means to cooperate with the matrices in their travel through the machine and deliver them at one point or another according to the location of their projecting ears.

7. In a typographical distributing machine equipped with matrices, each formed with the same tooth combination and with projecting ears, the latter being located at the left side of some and at the right side of other of said matrices, the combination of a distributor formed with a tooth combination to cooperate with those of the matrices and release said matrices at a common point, and means to cooperate with the released matrices and deliver them at one point or another according to the location of their projecting ears.

8. In a typographical distributing machine equipped with matrices, each formed with projecting ears, said ears being located at the left side of some and at the right side of other of said matrices, the combination of a distributor constructed to release mat-

rices of both forms at a common point, and means to cooperate with the released matrices and deliver them at one point or another according to the location of their projecting ears.

9. In a typographical distributing machine, two sets of matrices, each formed on its opposite edges with projecting ears, the said ears being located at the left side of the matrices of one set and at the right side of the matrices of the other set, in combination with distributing mechanism to cooperate with said matrices and deliver them at one point or another according to set.

10. In a typographical distributing machine, two sets of matrices, each formed with a distributing combination and with projecting ears, the distributing combinations of the matrices of one set being the same as those of the matrices of the other set, and the projecting ears being located at opposite sides of the matrices in the respective sets, in combination with distributing mechanism to cooperate with said matrices and deliver them at one point or another according to set.

11. In a typographical distributing machine, two sets of matrices each formed at its upper end with a tooth combination and on its opposite edges with projecting ears, the tooth combinations of the matrices of one set being the same as those of the matrices of the other set, and the projecting ears being located at opposite sides of the matrices in the respective sets, in combination with distributing mechanism to cooperate with said matrices and deliver them at one point or another according to set.

In testimony whereof, I have affixed my signature hereto.

DAVID S. KENNEDY.
